UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 9, 1923. Serial No. 656,545.

This invention relates to manifolding typewriting machines of the continuous billing type, in which a composite sheet or web is fed around a cylindrical platen, the 5 web comprising several plies of work-sheets having successive corresponding forms printed thereon, said plies being sometimes separated from each other, and sometimes joined at their side edges to form a fan-folded web, the various plies having carbon-sheets interleaved therebetween, which are displaceable at intervals along the web to fresh sets of untyped forms. The invention relates more particularly to means to 10 facilitate the relative displacing or shifting between the carbon-sheets and the work-sheets.

One form of machine for handling this kind of work is disclosed in the patent to 20 Wernery & Smith, No. 1,132,055, dated March 16, 1915. Said machine comprises a cylindrical platen mounted in a swing-frame, by which it may be raised to an abnormal position, from its normal typing position, to facilitate the straightening-out of 25 that portion of the web containing the carbon-sheets, so that the displacing of the carbon-sheets and the work-sheets may be readily effected.

Another form of this general type of machine is disclosed in my co-pending application, Serial No. 650,615, filed July 10, 1923, in which that portion of the web containing the carbon-sheets is so conditioned 35 that there may be effected a relative shifting between the carbon-sheets and the work-sheets, without shifting the platen, the platen remaining always in its normal typing position. To this end, there is provided, in 40 the machine of my aforesaid co-pending application, means for withdrawing the web completely from the platen, thus to bring it to a straightened-out position so that the work-sheets may be drawn forwardly, while 45 the carbon-sheets are held, to shift them relatively to the carbon-sheets. A table is provided, in the machine of my aforesaid co-pending application, having a pivoted section which may be swung to bring the 50 web to a convenient gaging and tearing-off position, said table being also effective to render effective certain devices to prevent accidental forward movement of the carbon-sheets during a work-sheet-gaging opera-

tion and to hold the work-sheets against accidental displacing during the tearing-off operation. Said machine also includes means for rapidly reinserting the web around the platen, there being provided, for this purpose, web-feeding means to advance 60 the web against a guide disposed at the back of the platen to conduct the leading edge of the web downwardly around the platen.

A feature of the present invention is the provision of feed-rollers for reinserting the 65 work-web around the platen, said feed-rollers being effective not only to advance the web but also to conduct it downwardly towards the platen.

A further feature of the invention relates 70 to a novel arrangement of sheet-gage and knife, and a connection by which they may be operated by a single handle.

Still another feature of the invention relates to novel means for preventing accidental 75 forward movement of the carbon-sheets during a work-sheet-gaging operation, there being provided, for this purpose, means connected with the gage-operating handle to co-operate with the carbon-carrier-actuating 80 handle to hold the carbon-carrier in its retracted position when the gage is swung to its effective position.

A further feature of the invention resides in means comprising a clamp to hold the 85 work-sheets to prevent accidental forward movement thereof during a form-severing operation, said clamp being operable by a further movement of the gage-operating handle, said movement being effective to 90 bring the knife to its fully-operated or effective position after the sheets have been gaged. The knife and the gage are so disposed that the web may be severed by drawing it upwardly against said knife away 95 from the platen.

Other features and advantages will hereinafter appear.

In the accompanying drawings,

Figure 1 is a sectional side view of a portion of an Underwood typewriting machine, showing the invention applied thereto, the parts being in their normal typing position, and a form nearing its completion of typing.

Figure 2 is a top plan view of the machine, with the parts in the position shown in Figure 1.

Figure 3 is a view similar to Figure 1,

and shows the feed-rollers cast off and the web completely withdrawn around the platen to free it from said platen; the web having also been brought to a straightened-out 5 position preparatory to a work-sheet-shifting operation.

Figure 4 is a view, similar to Figure 3, with some of the parts omitted, showing the gage swung to its effective position, the 10 work-sheets shifted relatively to the carbon-sheets, and the carbon-carrier-actuating handle held against forward movement to prevent accidental forward movement of the carbon-sheets during the work-sheet-gaging 15 operation.

Figure 5 is a view similar to Figure 4, and shows the gage-operating handle moved further from the position shown in Figure 4 to completely actuate the knife to bring 20 it to its effective position, and also clamp the web so as to prevent accidental forward movement of said web during the form-severing operation, the typed forms being severed in this figure.

Figure 6 is a diagrammatic sectional side view, showing the leading end of the web bent downwardly towards the platen by a 25 preliminary movement of the web-reinserting handle.

Figure 7 is a view similar to Figure 6, and shows the web-reinserting handle completely actuated to advance the web around the platen to the printing point.

The invention is shown as applied to an 30 Underwood standard typewriting machine, in which type-bars 10, when operated by keys, not shown, swing upwardly and rearwardly to print against the front of a cylindrical platen 11, mounted on a carriage 12 comprising end bars 13 connected to each other by a rear bar 14 and a front bar, not shown, said carriage being mounted for letter-feed movements on a rear rail 15 and a front rail, not shown, said rails being supported on the main frame 16 of the machine. The platen is secured to a shaft 17 journaled in end plates 18 of a platen-frame 20, said end plates being secured to each other by a bar 21 and a rear paper-table 22, over which a composite work-web 23 is led from the back of the machine to the rear and beneath the platen where there are provided feed-rollers 24 and 25 to assist in feeding the work-web around the platen. The platen 35 may be rotated by a finger-wheel 26 or line-space wheel 27, the latter being operable by suitable line-space mechanism, not shown. The platen-frame is supported on the carriage-frame for case-shifting movements in the usual way to present the platen to lower-case types 30 or upper-case types 31 on the type-bars. The feed-rollers may be released by mechanism operable by the regular feed-roller release-handle 28, so as to provide an 40 unobstructed path around the platen when

adjusting the work-web around the platen.

The attachment comprises a horizontal table 32 extending rearwardly from the machine, and over which the composite web 23, comprising work-sheets 33 with interleaved carbon-sheets 34, is conducted to the platen. The table 32 comprises end bars 37 connected to each other by a front cross-bar 40 and a rear cross-bar 41, and is supported to travel with the carriage 12. The table 32 is connected with said carriage by rearwardly-extending brackets 42 secured to the under side of the carriage-bar 14 and to the under side of the cross-bar 40 of said table. The table 32 is supported at its rear by means comprising brackets 43 secured to the end bars 37 thereof. The brackets 43 have rollers 44 to run on a rod 45 secured to a frame comprising two end plates 46 extending rearwardly of the main frame 16 of the type-writer.

The two end bars 37 have rails 52 secured thereto to guide a carbon-carrier 53 towards and away from the platen. The carbon-carrier 53 comprises a base-plate 54, to the under side of which are attached four rollers 55, two at each side of the machine, to run on the rails 52. The carbon-carrier further comprises stepped uprights 56, one at each side of the machine, on which carbon blades or holders 57 are detachably mounted, said carbon-blades having the rear ends of the carbon-sheets 34 connected thereto. The work-web, which may be fan-folded or be composed of separated plies, may be conducted from any suitable source of supply upwardly at the rear of the machine to a turning bar 60, supported by standards 61 and provided with suitable end gages 62 for the web 23. The web is then conducted forwardly through the carbon-carrier and over a roller 63 toward the platen. The roller 63 is journaled in the forward ends of the end bars 37 of the table 32. Suitable end gages 64 on the bar 40 further guide the web. From the roller 63 the web is conducted downwardly to the platen, between the feed-rollers 24 and 25 and upwardly at the front across the printing point, where the web may be held against the platen by the usual wing-scales (not shown) and one or more fingers 59 extending rearwardly towards the platen from the usual front rail of the carriage.

As the typing of a form proceeds, the carbon-carrier 53 travels towards the platen on the table 32. When the typing of a form has been completed, it is desirable to sever the typed forms from the work-sheets. Before this is done, however, it is necessary to shift the carbon-sheets relatively to the work-sheets to a fresh set or untyped set of forms. To do this, the composite web is withdrawn around the platen to free it from the said platen, so that that portion of the composite

web including the carbon-sheets 34 may be brought to a straightened-out position, the platen retaining its usual typing position, after which the work-sheets may be shifted 5 relatively to the carbon-sheets.

When it is desired to straighten out the composite web, the feed-rollers 24 and 25 are first cast off by depressing the usual feed-roller release-handle 28. The carbon- 10 carrier is then pushed rearwardly by means of a handle 65 extending forwardly therefrom until it is arrested against a fixed stop 66 on the end bar 37, the parts being arrested in the position shown in Figure 3, 15 where the composite web has been cleared from the platen and has sprung up into a horizontal, straightened position, with the leading edges of the work-sheets over the platen where they are accessible to, and may be grasped by the operator, and with the web resting on the roller 63.

The next step is to set a gage for determining the position to which the leading edges of the work-webs are to be drawn, 20 while the carbon-sheets are held stationary, in effecting the form-to-form shift of the carbons relative to the work-webs, and in clearing the typed leading forms of the work-webs of the carbons, so that such typed 25 leading forms may be detached from the rest of the work-webs. This gage 70 is shown as adjustably secured to a staff 71, fast on a rock-shaft 72, pivoted in fixed brackets or plates 73 over the front of the 30 platen-frame. The brackets 73 are secured by screws 74, one to each of the bars 37 of the frame 32. The normal position of the gage and gage-staff is that shown in Figure 1. The operative position of the gage is 35 that shown in Figure 4, in which the gage-staff is shown as having been swung to a substantially horizontal position from a substantially vertical, Figure 1, position, and in which Figure 4 position the gage 70 is 40 shown as lying vertically across the horizontal path of the work-webs over the platen. For effecting the throw of the gage-staff from Figure 1 to Figure 4 position, there is fast to the right-hand end of the 45 rock-shaft 72 an arm 75, connected by a link 76 to a plate 77 made fast to a rock-shaft 78, also journaled at its ends in the bracket-plates 73. Fast to the left-hand end of the rock-shaft 78 is a lever 79, by means 50 of which the shaft 78, plate 77, link 76, arm 75 and rock-shaft 72 may be actuated, by upward throw of the lever 79, to throw down the gage-staff to Figure 4 position. When the gage 70 is in its Figure 4 position, the leading edges of the work-webs, 55 beyond the leading edges of the carbon-sheets, may be seized by the operator and drawn forward to the gage.

When the work-webs are thus drawn forward, the carbons should be held stationary

in their Figure 3 position. This might be done by the operator pressing rearward, with one hand, on the forward end of the handle 65 on the carbon-carrier. To relieve the operator of this duty, however, means 70 is provided for automatically locking the carbon-carrier in its Figure 3 position when the lever 79 is thrown from Figure 1 to Figure 4 position. Such means is shown as a rearwardly-extending arm 80, forming 75 part of the lever 79, and having a stop-piece 81 thereon, which, as shown in Figure 4, blocks the path of the finger-piece 82 on the end of the carbon-carrier arm 65 to prevent forward movement of the carbon-carrier 80 when the work-webs are pulled forward to Figure 4 position.

After the work-webs are in Figure 4 position, it is usually desirable to sever the typed leading forms thereof. This is effected by means of a knife-blade 83, which has a normal position, shown in Figures 1 and 3, well out of the way of the web, above the elevation of the table 32, and behind that part of the web which extends above the printing line. The effective position of the knife-blade 83 is that shown in Figure 5. For bringing the knife to Figure 5 position, the handle 79, which throws the gage-staff to Figure 4 position, is conveniently 95 utilized. For this purpose, the knife 83 is supported at one end upon the arm or plate 77 to which the staff-link 76 is connected, and at its other end upon a similar arm or plate 84, fast to the rock-shaft 78, so that, 100 when the handle 79 is thrown up to lower the gage-staff, the knife 83 is also lowered to the horizontal Figures 4 and 5 path of the web. As indicated in Figure 4, however, a position for the knife 83, intermediate its 105 Figures 1 and 5 positions, is provided, in which intermediate position the knife-blade is at a slight incline and somewhat to the rear of the leading edges of the work-webs before they have been drawn to the gage 70. This intermediate position of the knife-blade permits the work-webs to be grasped, as above stated, for the form-to-form shift of the same relative to the carbons. Such 110 relative form-to-form shift of the webs and carbons having been effected, however, the knife, by a further upward movement of the handle 79, may be brought from Figure 4 to Figure 5 position. Owing to the length of the stop-piece 81 on the rear arm 80 of the lever 79, this further upward movement of the lever will not clear the stop-piece 81 from the path of the end of the carbon-carrier-operating arm 65, and, therefore, accidental forward displacement of the carbon-carrier cannot take place, such as might otherwise result in blocking the return of the lever 79 to its normal, Figure 1, position. Furthermore, by reason of the continued presence of the stop 81 in the path 115

- of the carbon-carrier-operating arm 65, the carbons cannot be displaced forward during the operation of drawing the webs against the knife 83, as shown in Figure 5, to sever the leading typed form-sections. The full throw, to Figure 5 position, of the lever 79, and, consequently, the effective position of the knife 83, is determined by means presently to be described.
- 10 Prior to severing the leading form-sections of the work-webs, it is desirable not only that the carbons be held against forward displacement, but that the work-webs themselves be held against such displacement.
- 15 Consequently, a clamping bar 86 is provided, between which and a bar 87, supported on blocks 88 on the table-rails 37, the composite may be clamped at the proper time. The clamping bar 86, supported at its ends by
- 20 arms 89 fast on a rock-shaft 90 journaled in the bracket-plates 73, is normally held in Figures 1 and 4 positions above and out of the path of the web. The effective position of the clamping bar 86 is that shown in Figure 5. For throwing the clamping bar to Figure 5 position, the handle 79 is again conveniently utilized; and the connection from the clamp-bar-supporting arms 89 to the lever 79 is by means of a link 91, connected at its rear end to an arm 92 forming a bell-crank with the right-hand arm 89, and at its front end bearing a pin 93 working in a slot 94 in the right-hand knife-supporting plate 77. It is obvious that, when the
- 25 gage is thrown to Figure 4 position for the forward shift of the work-webs, the clamping bar 86 should not be effective to perform its function; otherwise, the clamping bar will prevent the forward shift of the
- 30 work-webs. It is for this reason that the pin-and-slot connection 93—94 is provided between the link 91 and the handle 79. This slot is of such length that, as the handle is moved from Figure 1 to Figure 4 position,
- 35 the pin 93 traverses the slot 94 without movement of the link 91. Further movement of the lever 79, from Figure 4 to Figure 5 position, for setting the knife, after the forward shift of the work-webs, results in a pull
- 40 on the link 91, because, as shown in Figure 4, the pin 93 is then at the rear end of the slot 94. This pull on the link 91, by movement of the lever 79 to Figure 5 position, results in the clamping bar 86 being rocked down
- 45 against the web to hold the latter fixed against the plate 87. The leading typed section of the web may then be seized and drawn against the blade 83, without possibility of such movement of the web behind the blade 83 as might affect the accuracy of
- 50 the cut. Engagement of the clamp 86 with the plate 87 determines the upward throw of the lever 79 and effective position of the knife 83.
- 55 The handle 79 is then rocked downward

from Figure 5 to its normal, Figure 1, position. This normal position may be determined by engagement of the rear edge of the right-hand knife-carrying plate 77 with a stop-pin 95 fixed on the adjacent bracket-plate 73. A coil spring 96, having one end hooked over the upper edge of the right-hand bracket-plate 73, and having its other end hooked over the front edge of the adjacent knife-supporting plate 77, may act to return the parts to normal position when the lever 79 is released, and to hold the same in normal position against displacement. During the early portion of this return movement, the knife-blade 83 and clamping bar 86 are first returned to Figure 4 position. Thereafter, the lever 79 moves without movement of the clamping bar; the pin 93 merely moving to the front end of the slot 94 as the lever 79 completes its throw. The front end of the slot 94 may serve to determine the normal position of the clamping bar. When the lever 79 is in its normal position, the carbon-carrier is again free for forward movement, so that the composite web may be fed down behind the platen and around the latter, to position for commencement of writing.

As a preliminary to positioning the composite web for commencement of writing, the same is bent downward over the paper-shelf 22, forward of the roller 63, as indicated in Figure 6. This bending of the web is effected by movement of a roller 97, from Figure 1 to Figure 6 position, against the roller 63. The roller 97 is journaled on arms 98 made fast to a rock-shaft 99, in turn journaled at its ends in the bracket-plates 73. Forming a bell-crank with the right-hand arm 98 is an arm 100, in the end of which is journaled a stub-shaft 101. Fast to the shaft 101 is an operating lever 102; and also fast to the shaft 101 is a segmental rack 103, the purpose of which will present appear. A coil spring 104 connects an ear 105 on the segmental rack 103 with an ear 106 on the lever 98. The tension of the spring 104 is such as to prevent rotary movement of the segmental rack 103, stub-shaft 101 and lever 102 on the arm 100; so that a downward pull on the lever 102, from Figure 1 to Figure 6 position, simply causes rotary movement of the lever 102 and roll-carrying arms 98 as a unit with the rock-shaft 99 around the axis of the latter, until the roll 97 bears against the roll 63. The roll 97, in its movement to the roll 63, strikes the horizontally-projecting end of the composite web and deflects the same from Figure 3 to Figure 6 position.

On reference to Figure 6, it will be noted that forward feed of the web from the position therein shown will result in movement of the web around under the platen, between the latter and the then released feed-rolls 24

and 25. This feed of the composite web, and the extent of such feed to properly position the web for commencement of typing, are effected and determined by the following means: The rack 103 is in mesh with a pinion 107 concentric with and fast to the roll 97. Owing to the strength of the spring 104, as hereinbefore set forth, no rotary movement of the rack 103, and, consequently, of the pinion 107, takes place in movement of the operating lever 102 from Figure 1 to Figure 6 position; the parts, up to this time, turning on the axis 99. Upon engagement of the roll 97 with the roll 63, however, further movement of the lever 98—100 on the axis 99 is prevented; and, thereafter, further pressure on the operating lever 102, sufficient to overcome the tension of the spring 104, results in the rotation of the stub-shaft 101, and consequently, of the rack 103. Such rotation of the rack 103 causes rotation of the pinion 107 and of the roll 97. The roll 97 being pressed against the roll 63, with the web between the same, and being rotated by the pinion 107, there results a forward downward feed of the composite web from Figure 6 to Figure 7 position. The Figure 7 position which is the position of the web for commencement of typing, is determined by engagement of the forward end of a slot 108 in the rack 103 with a pin 109 which projects into the slot 108 from the lever-arm 100. Upon release of the lever 102, a coil spring 110, having one end thereof hooked under the right-hand roll-carrying arm 98, and the other end thereof hooked over the adjacent bracket-plate 73, lifts the arm 98 and rotates the rock-shaft 99 to release the roll 97 from the roll 63. The spring 104, when the handle 102 is released, returns the handle 102 and rack 103 from Figure 7 to Figure 6 position; the pin 109, by engagement with the opposite end of the slot 108, determining the Figure 6, or normal, position of the rack and operating lever 102 on the lever-arm 100. A stop-pin 111 on the right-hand bracket-plate 73, by engagement with the upper edge of the right-hand roll-carrying arm 98, determines the Figure 1, or normal, position of the roll 97 and associated parts. It will be noted that the spring 104 is stronger than the spring 110, so that the latter yields to permit movement of the parts as a unit around the axis 99, from Figure 1 to Figure 6 position, before the former yields to permit rotation of the handle 102 and rack 103 around the axis 101. The feed-rolls 24 and 25 may then be re-applied to the platen, and typing commenced.

60 Variations may be resorted to within the scope of the invention, and portions of the improvements may be used without others.

Having thus described my invention, I claim:

65 1. In a typewriting machine, a platen, a

platen-carriage, a table on the platen-carriage extending rearward therefrom, means for directing a multiple-ply continuous web, interleaved with carbons, over the table, a cross-piece at the front end of the table, at a higher elevation than the platen, and around which the web may be turned for guidance therefrom down and around the platen, means for effecting line-spaced feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading typed portion of the work-webs to an untyped portion of the work-webs, means for severing the typed portion of the work-webs above the platen, and means movable, from a normally ineffective position, against the forward portion of the cross-piece at the front of the table, to deflect the leading portion of the web, after such severance, from the plane in which the web approaches the platen-carriage to a plane in which the web is directed down toward the platen.

2. In a typewriting machine, a platen, a platen-carriage, a table on the platen-carriage extending rearward therefrom, means for directing a multiple-ply continuous web, interleaved with carbons, over the table, a roller at the front end of the table, at a higher elevation than the platen, and around which the web may be turned for guidance therefrom down and around the platen, means for effecting line-space feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading typed portion of the work-webs to an untyped portion of the work-webs, means for severing the typed portion of the work-webs above the platen, and another roller movable, from a normally ineffective position, against the forward portion of the first-mentioned roller at the front of the table, to deflect the leading portion of the web, after such severance, from the plane in which the web approaches the platen-carriage to a plane in which the web is directed down toward the platen.

3. In a typewriting machine, a platen, a platen-carriage, a table on the platen-carriage extending rearward therefrom, means for directing a multiple-ply continuous web, interleaved with carbons, over the table, a roller at the front end of the table, at a

higher elevation than the platen, and around which the web may be turned for guidance therefrom down and around the platen, means for effecting line-space feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading type portions of the work-webs to an untyped portion of the work-webs, means for severing the typed portion of the work-webs above the platen, another roller movable, from a normally ineffective position, against the forward portion of the first-mentioned roller at the front of the table, to deflect the leading portion of the web, after such severance, from the plane in which the web approaches the platen-carriage to a plane in which the web is directed down toward the platen, and means for rotating the last-mentioned roller, after engagement thereof with the first-mentioned roller, for feeding the composite web down and around the platen into position for commencement of typing upon the web.

4. In a typewriting machine, a platen, a platen-carriage, a table on the platen-carriage extending rearward therefrom, means for directing a multiple-ply continuous web, interleaved with carbons, over the table, a roller at the front end of the table, at a higher elevation than the platen, and around which the web may be turned for guidance therefrom down and around the platen, means for effecting line-space feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading typed portion of the work-webs to an untyped portion of the work-webs, means for severing the typed portion of the work-webs above the platen, another roller movable, from a normally ineffective position, against the forward portion of the first-mentioned roller at the front of the table, to deflect the leading portion of the web, after such severance, from the plane in which the web approaches the platen-carriage to a plane in which the web is directed down toward the platen, and means for rotating the last-mentioned roller, after engagement thereof with the first-mentioned roller, for feeding the composite web down and around the platen into position for commencement of typing upon the web, com-

prising a pinion on the last-mentioned roller, a gear in mesh with the pinion, and a handle for turning the gear.

5. In a typewriting machine, a platen, a platen-carriage, a table on the platen-carriage extending rearward therefrom, means for directing a multiple-ply continuous web, interleaved with carbons, over the table, a roller at the front end of the table, at a higher elevation than the platen, and around which the web may be turned for guidance therefrom down and around the platen, means for effecting line-space feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading typed portion of the work-webs to an untyped portion of the work-webs, means for severing the typed portion of the work-webs above the platen, another roller movable, from a normally ineffective position, against the forward portion of the first-mentioned roller at the front of the table, to deflect the leading portion of the web, after such severance, from the plane in which the web approaches the platen-carriage to a plane in which the web is directed down toward the platen, a rocker in which the last-mentioned roller is journaled, a lever for moving the rocker to bring the roller thereon into engagement with the first-mentioned roller, and means operable by the lever to rotate the roller on the rocker, after the rollers are in engagement, for feeding the web around the platen into position for commencement of writing on the web.

6. In a typewriting machine, a platen, a platen-carriage, a table on the platen-carriage extending rearward therefrom, means for directing a multiple-ply continuous web, interleaved with carbons, over the table, a roller at the front end of the table, at a higher elevation than the platen, and around which the web may be turned for guidance therefrom down and around the platen, means for effecting line-space feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading typed portion of the work-webs to an untyped portion of the work-webs, means for severing the typed portion of the work-webs above the platen, another roller movable, from a normally ineffective position, against the forward portion of the first-mentioned roller at the front of the table, to deflect the leading portion of the web, after such severance, from the plane in which the web approaches the platen-carriage to a plane in which the web is directed down toward the platen, and means for rotating the last-mentioned roller, after engagement thereof with the first-mentioned roller, for feeding the composite web down and around the platen into position for commencement of typing upon the web, com-

first mentioned roller at the front of the table, to deflect the leading portion of the web, after such severance, from the plane in which the web approaches the platen-carriage to a plane in which the web is directed down toward the platen, a rocker in which the last-mentioned roller is journaled, a lever for moving the rocker to bring the roller thereon into engagement with the first-

10 mentioned roller, and means operable by the lever to rotate the roller on the rocker, after the rollers are in engagement, for feeding the web around the platen into position for commencement of writing on the web, comprising a pinion fast to the roller on the rocker, a rack on the rocker, a shaft on which the rack and the lever are revoluble as a unit on the rocker, and a spring for preventing rotation of the lever and rack until after the rollers are in engagement, and for permitting rotation of the lever and rack after the rollers are in engagement.

7. In a typewriting machine, a platen, a platen-carriage, a table on the platen-carriage extending rearward therefrom, means for directing a multiple-ply continuous web, interleaved with carbons, over the table, a roller at the front end of the table, at a higher elevation than the platen, and around which the web may be turned for guidance therefrom down and around the platen, means for effecting line-space feed of the composite web around the platen for typing on the leading portion thereof, means for releasing the composite web and retracting the typed portion thereof rearward to free the same from the platen and to permit the same to spring into a position above the platen, means for effecting a relative shift of the carbons and work-webs to shift the carbons from the leading typed portion of the work-webs to an untyped portion of the work-webs, means for severing the typed portion of the work-webs above the platen, another roller movable, from a normally ineffective position, against the forward portion of the first-mentioned roller at the front of the table, to deflect the leading portion of the web, after such severance, from the plane in which the web approaches the platen-carriage to a plane in which the web is directed down toward the platen, a rocker in which the last-mentioned roller is journaled, a lever for moving the rocker to bring the roller thereon into engagement with the first-mentioned roller, and means operable by the lever to rotate the roller on the rocker, after the rollers are in engagement, for feeding the web around the platen into position for commencement of writing on the web, comprising a pinion fast to the roller on the rocker, a rack on the rocker, a shaft on which the rack and the lever are revoluble as a unit on the rocker, a spring for preventing rotation of the lever and rack until after

the rollers are in engagement, and for permitting rotation of the lever and rack after the rollers are in engagement, and another spring for returning the rocker to normal position, the last-mentioned spring being weaker than the first-mentioned spring, so that the rollers may be brought into engagement before rotary movement of the rack takes place.

8. In a typewriting machine, a platen, a platen-carriage, a table in fixed position on the platen-carriage and extending rearward therefrom, means for directing a multiple-
ply continuous web, interleaved with carbons, forward over the table, a cross-piece
at the front end of the table, at a higher
elevation than the platen, and around which
the web may be turned for guidance there-
from down and around the platen, means for
effecting line-space feed of the composite
web around the platen for typing on the
leading portion thereof, means for releasing
the composite web and retracting the typed
portion thereof rearward to free the same
from the platen and to permit the same to
spring into a position above the platen,
means to which the work-webs may be moved
relatively to the carbons, over and to the
front of the platen, while the carbons are
held against such movement, for effecting
relative shift of the work-webs and carbons,
means for severing the leading typed portion
of the work-webs, and a device for de-
flecting the leading untyped portion of the
composite web downward behind the platen,
and thereafter feeding the web downward
and around the platen to position for recom-
mencement of typing.

9. In a typewriting machine, a platen, a platen-carriage, means for positioning a work-piece in a plane directed toward the carriage, means movable, from a normally ineffective typing position, to a position in which it engages the leading portion of the work-piece to deflect the same from its aforesaid plane to a plane in which it is directed toward the platen, means for moving said deflecting means to cause the same to feed the work-piece to the platen, and means for determining a throw of such deflecting means which will determine the correct position of the work-piece on the platen for commencement of typing on the work-piece. 110 115 120

mine the correct position of the work-piece on the platen for commencement of typing on the work-piece.

11. In a typewriting machine, a platen, a carriage for the platen, a table on the carriage, over which a multiple-ply web, interleaved with carbons, may be fed to the carriage, a gage to which the leading ends of the work-webs may be drawn over and above the platen, while the carbons are retracted, to effect relative shift of the carbons and work-webs, and means for moving the gage from a normally ineffective position to a position forward of the platen and in a horizontal path for the work-webs over the platen, said gage-moving means comprising a staff or arm, a shaft on which the arm is pivoted above the platen, a link connected to the arm, another arm to which the link is also connected, and a lever for throwing the last-mentioned arm.

12. In a typewriting machine, a platen, a carriage for the platen, a table on the carriage, over which a multiple-ply web, interleaved with carbons, may be fed to the carriage, a gage to which the leading ends of the work-webs may be drawn over and above the platen, while the carbons are retracted, to effect relative shift of the carbons and work-webs, and means for moving the gage from a normally ineffective position to a position forward of the platen and in a horizontal path for the work-webs over the platen, said gage-moving means comprising a staff or arm, a shaft on which the arm is pivoted above the platen, a link connected to the arm, another arm to which the link is also connected, and a lever for throwing the last-mentioned arm, the connections being such that movement of the operating lever causes the gage-supporting arm to move from a substantially vertical position behind the path of the web above the printing line, when the parts are in typing position, to a substantially horizontal position below the path of the web over the platen in which the shift of the same relative to the carbons is effected.

13. In a typewriting machine, a platen, a platen-carriage, means for directing, forward to the carriage, a multiple-ply web interleaved with carbons, a gage movable from a normally ineffective position behind the path of the web above the printing line to an effective position forward of the platen, in which effective position the work-webs may be drawn in straightened condition over and above the platen for effecting shift of the same with respect to the carbons, a severing blade for the web, having a normal or typing position away from such straightened path for the web above the platen, and an effective position at such straightened path, and means connected to both the gage and the blade for moving the gage and the blade

together from their normal positions to their effective positions, such means having a certain stroke to position the gage and a further stroke thereafter effectively to position the blade; so that the leading edges of the work-webs may be seized by the operator for movement to the gage before the blade is finally positioned.

14. In a typewriting machine, a platen, a platen-carriage, means for directing, forward to the carriage, a multiple-ply web interleaved with carbons, a gage movable from a normally ineffective position behind the path of the web above the printing line to an effective position forward of the platen, in which effective position the work-webs may be drawn in straightened condition over and above the platen for effecting shift of the same with respect to the carbons, a severing blade for the web, having a normal or typing position away from such straightened path for the web above the platen, and an effective position at such straightened path, and means for moving the gage to its effective position and for moving the blade downward toward the path of the web to a position where the web may yet be seized by the operator for movement thereof to the gage, and thence for moving the blade forward along the path of the web to its position for severing the web.

15. In a typewriting machine, a platen, a platen-carriage, means for directing, forward to the carriage, a multiple-ply web interleaved with carbons, a gage movable from a normally ineffective position behind the path of the web above the printing line to an effective position forward of the platen, in which effective position the work-webs may be drawn in straightened condition over and above the platen for effecting shift of the same with respect to the carbons, a severing blade for the web, having a normal or typing position away from such straightened path for the web above the platen, and an effective position at such straightened path, and means for moving the gage to its effective position and for moving the blade downward toward the path of the web to a position where the web may yet be seized by the operator for movement thereof to the gage, and thence for moving the blade forward along the path of the web to its position for severing the web, the gage and blade being connected for movement together, and the operating means therefor having one stroke to bring the gage to its effective position and the blade to its aforesaid preliminary position in which the leading ends of the work-webs are exposed, and a further stroke to bring the blade to final position.

16. In a typewriting machine, a platen, a platen-carriage, means for directing, forward to the carriage, a multiple-ply web interleaved with carbons, a gage movable from a

- normally ineffective position behind the path of the web above the printing line to an effective position forward of the platen, in which effective position the work-webs may 5 be drawn in straightened condition over and above the platen for effecting shift of the same with respect to the carbons, a severing blade for the web, having a normal or typing position away from such straightened path 10 for the web above the platen, and an effective position at such straightened path, and means for moving the gage to its effective position and for moving the blade downward toward the path of the web to a position 15 where the web may yet be seized by the operator for movement thereof to the gage, and thence for moving the blade forward along the path of the web to its position for severing the web, the gage and blade being 20 connected for movement together, and the operating means therefor comprising a pivoted lever movable a certain distance to bring the gage to its effective position and the blade to its aforesaid preliminary position 25 in which the leading ends of the work-webs are exposed, and being movable a further distance in the same direction to bring the blade to final position.
17. In a typewriting machine, a platen, a 30 platen-carriage, means for directing, forward to the carriage, a multiple-ply web interleaved with carbons, a gage movable from a normally ineffective position behind the path of the web above the printing line to an 35 effective position forward of the platen, in which effective position the work-webs may be drawn in straightened condition over and above the platen for effecting shift of the same with respect to the carbons, a severing blade for the web, having a normal or 40 typing position away from such straightened path for the web above the platen, and an effective position at such straightened path, means for moving the gage to its effective 45 position and for moving the blade downward toward the path of the web to a position where the web may yet be seized by the operator for movement thereof to the gage, and thence for moving the blade forward along the path of the web to its position for severing the web, the gage and blade being 50 connected for movement together, and the operating means therefor having one stroke to bring the gage to its effective position and the blade to its aforesaid preliminary position in which the leading ends of the work-webs are exposed, and a further stroke to bring the blade to final 55 position, means for clamping the web against accidental displacement during the severing operation, after the leading ends of the web have been drawn to the gage, and means connecting the clamp to the blade-operating means so that the latter may operate both the blade and the clamp; the connections between the blade and the clamp being such that the clamp is ineffective when the blade 60 is in its preliminary position for permitting movement of the work-webs to the gage, and becomes effective when the blade receives its final movement to severing position.
19. In a typewriting machine, a platen, a platen-carriage, means for directing, forward to the carriage, a multiple-ply web interleaved with carbons, a gage movable from a normally ineffective position behind the path of the web above the printing line to an effective position forward of the platen, in which effective position the work-webs may be drawn in straightened condition over and above the platen for effecting shift of the same with respect to the carbons, a severing blade for the web, having a normal or 65 typing position away from such straightened path for the web above the platen, and an effective position at such straightened path, means for moving the gage to its effective position and for moving the blade downward toward the path of the web to a position where the web may yet be seized by the operator for movement thereof to the gage, and thence for moving the blade forward along the path of the web to its position for 70 severing the web, the gage and blade being connected for movement together, and the operating means therefor having one stroke to bring the gage to its effective position and the blade to its aforesaid preliminary position in which the leading ends of the work-webs are exposed, and a further stroke to bring the blade to final position, means for clamping the web against accidental displacement during the severing operation, after the leading ends of the web have been drawn to the gage, and means connecting the clamp to the blade-operating means so that the latter may operate both the blade and the clamp.

sition for severing the web, the gage and blade being connected for movement together, and the operating means therefor having one stroke to bring the gage to its effective position and the blade to its aforesaid preliminary position in which the leading ends of the work-webs are exposed, and a further stroke to bring the blade to final position, means for clamping the web against accidental displacement during the severing operation, after the leading ends of the web have been drawn to the gage, and means connecting the clamp to the blade-operating means so that the latter may operate both the blade and the clamp; the blade and the clamp having a pin-and-slot connection with each other so that the clamp is ineffective when the blade is in its preliminary position for permitting movement of the work-webs to the gage, and becomes effective when the blade receives its final movement of severing position.

20. In a typewriting machine, a platen, a platen-carriage, a table over which a multiple-ply web, interleaved with carbons, may be directed to the carriage, a carrier on the table to which the carbons are connected at their rear, and which is movable toward the platen for line-space feed of the web around the platen in the typing operation, means for moving the carbon-carrier rearward on the table for conditioning the web for relative shift of the carbons and work-webs, a gage to which the leading ends of the work-webs may be drawn while the carbon-carrier is retracted, for effecting such relative shift of the carbons and work-webs, means for moving the gage from its normal or typing position to its effective position, and means connected to the gage-operating means for locking the carbon-carrier in retracted position when the gage is moved to effective position.

21. In a typewriting machine, a platen, a platen-carriage, a table over which a multiple-ply web, interleaved with carbons, may be directed to the carriage, a carrier on the table to which the carbons are connected at their rear, and which is movable toward the platen for line-space feed of the web around the platen in the typing operation, a handle connected to the carbon-carrier for moving the carbon-carrier rearward on the table for conditioning the web for relative shift of the carbons and work-webs, a gage to which the leading ends of the work-webs may be drawn while the carbon-carrier is retracted, for effecting such relative shift of the carbons and work-webs, means for moving the gage from its normal or typing position to its effective position, and means connected to the gage-operating means for movement into the path of the carbon-carrier handle, when the gage is moved to effective position, to hold the carbons retracted

during the shift of the work-webs to the gage.

22. In a typewriting machine, a platen, a platen-carriage, a table over which a multiple-ply web, interleaved with carbons, 70 may be directed to the carriage, a carrier on the table to which the carbons are connected at their rear, and which is movable toward the platen for line-space feed of the web around the platen in the typing operation, 75 a handle connected to the carbon-carrier for moving the carbon-carrier rearward on the table for conditioning the web for relative shift of the carbons and work-webs, a gage to which the leading ends of the work-webs may be drawn while the carbon-carrier is retracted, for effecting such relative shift of the carbons and work-webs, and means for moving the gage from its normal or typing position to its effective 80 position; the gage-operating means comprising a lever having a shoulder thereon for movement into the path of the carbon-carrier handle, when the gage is moved to effective position, to hold the carbons retracted during the shift of the work-webs to the gage.

23. In a typewriting machine, a platen, a platen-carriage, a table over which a multiple-ply web, interleaved with carbons, may be directed to the carriage, a carrier on the table to which the carbons are connected at their rear, and which is movable toward the platen for line-space feed of the web around the platen in the typing operation, means 95 for moving the carbon-carrier rearward on the table for conditioning the web for relative shift of the carbons and work-webs, a gage to which the leading ends of the work-webs may be drawn while the carbon-carrier is retracted, for effecting such relative shift of the carbons and work-webs, means for moving the gage from its normal or typing position to its effective position, means 100 connected to the gage-operating means for locking the carbon-carrier in retracted position when the gage is moved to effective position, and a blade connected to the gage-operating means for movement to an effective position wherein the leading sections of the work-webs, after the work-webs have been moved to the gage, may be severed from the rest of the web while the carbon-carrier is locked, as aforesaid, in retracted position.

24. In a typewriting machine, a platen, a table over which a multiple-ply web, interleaved with carbons, may be fed to the carriage, a carbon-carrier movable forward with the carbons on the table for line-spacing and typing on the web, means for moving the carbon-carrier rearward on the table to condition the web for relative shift of the carbons and work-webs, a gage to which the work-webs may be drawn for such relative shift, and means common to the gage 125 130

and to the means for moving rearward the carbon-carrier, for locking the carbon-carrier in retracted position and for moving the gage to effective position, so that the 5 carbons may be held against forward displacement when the work-webs are drawn to the gage.

25. In a typewriting machine, a platen and a carriage therefor, a rearwardly-disposed table extending from the carriage, over which a multiple web interleaved with carbons may be fed to the platen, bracket-plates above the platen attached to the front of the table, one on each side thereof, gaging 10 means to which the web may be drawn to determine the length to be severed therefrom, rockably mounted between the bracket-plates, web-severing means rockably mounted between the bracket-plates, means 15 connecting the gaging means and the web-severing means for movement in unison, an operating lever for rocking the web-severing means to effective or operative position, means rockably mounted between the bracket-plates for clamping the web against accidental displacement during the severing operation, and a connecting link between 20 said clamping means and said web-severing means, one end of said link being pivotally 25 connected to the clamping means and the other end having a pin-and-slot connection with the web-severing means, so that upon initial movement of the operating lever to rock the web-severing means to its effective 30 or operative position, and incidentally the 35 gaging means, the clamping means will remain ineffective, said clamping means becoming effective upon the completed movement of the operating lever.

40 26. In a typewriting machine, a platen and a carriage therefor, a rearwardly-dis-

posed table extending from the carriage, over which a multiple web interleaved with carbons may be fed to the platen, a carbon-carrier and carbons movable forward on 45 the table, a handle for moving the carbon-carrier rearward on the table to condition the web for relative shifting of the carbons and work-webs, bracket-plates above the platen attached to the front portion of the 50 table, one on each side thereof, gaging means to which the web may be drawn to determine the length to be severed therefrom, rockably mounted between the bracket-plates, means connecting the gaging means 55 and the web-severing means for movement in unison, an operating lever for rocking the web-severing means to effective or operative position, an arm extending from the operating lever in the path of the carbon-carrier handle to abut against the handle and to lock the carbon-carrier in its most rearward position, upon the web-severing means being thrown to its effective 60 or operative position by the operating lever, 65 means rockably mounted between the bracket-plates for clamping the web against accidental displacement during the severing operation, and a connecting link between said clamping means and said web-severing 70 means, one end of said link being pivotally connected to the clamping means and the other end having a pin-and-slot connection with the web-severing means, so that upon initial movement of the operating lever to 75 rock the web-severing means to its effective or operative position, the clamping means will remain ineffective, said clamping means becoming effective upon the completed movement of the operating lever.

JOHN WALDHEIM.
